UNITED STATES PATENT OFFICE.

CLEMENS B. NAGELMANN, OF SANTA BARBARA, CALIFORNIA.

INTERNAL-COMBUSTION ENGINE.

Application filed March 1, 1923. Serial No. 622,132.

To all whom it may concern:

Be it known that I, CLEMENS B. NAGELMANN, a citizen of the United States, residing at Santa Barbara, in the county of Santa Barbara and State of California, have invented certain new and useful Improvements in Internal-Combustion Engines, of which the following is a specification, reference being had to the accompanying drawings.

This invention relates to internal combustion engines, particularly to engines of that type wherein the power of the pistons is transmitted to the driving shaft by means of an oscillatory disk or equivalent device.

One of the objects of this invention is to mount this disk or equivalent device so that it may be given the oscillatory rotary motion referred to without necessitating the use of means for preventing any rotation of the disk.

A further object is to provide an engine of this character with very simple valve mechanism for admitting motive fluid to the cylinders and exhausting the burnt gases therefrom.

A still further object is to so construct the engine that the cylinders may be readily kept cool and the valve mechanism kept cool and lubricated.

Another object is to provide an engine of this construction having a valve head common to all of the cylinders of the engine and driven by the shaft, thus making for extreme simplicity of valve mechanism, making the valve positive in its action, providing for ample valve openings, providing for a proper fit of the valve, and the valve being further so constructed that the pressure of gases acting on the valve head during the explosion stroke of any cylinder is in the direction toward the center of the valve, thus requiring only a relatively slight pressure to hold the valve head to its seat.

Other objects have to do with the details of construction and arrangement of parts as will appear more fully hereinafter.

My invention is illustrated in the accompanying drawings, wherein:

Figure 1 is a vertical sectional view through an engine constructed in accordance with my invention;

Figure 2 is a reduced plan view of the engine with the head removed;

Figure 3 is a similar view with the head in place;

Figure 4 is a bottom plan view of the rotatable valve structure;

Figure 5 is a diagram illustrating the operation of the valve.

Referring to these drawings, it will be seen that my engine comprises a plurality of cylinders 10 arranged in a series concentric to a common center and, as illustrated, these cylinders may be formed in an engine block 11 of any suitable character. Water spaces 12 will be formed between the cylinders in the engine block in any suitable manner so as to permit a circulation of water for the purpose of keeping the engine cool. The cylinder block is shown as formed with a central, vertical passage 13. The lower ends of the cylinders are open, and operating within the cylinders are the pistons 14 having the piston or connecting rods 15. The upper ends of the cylinders are formed by a cylinder head 16. This head is formed with a plurality of chambers 17, one for each cylinder 10, each chamber having an opening 18 to the corresponding cylinder. The inner face of the head 16 is downwardly and centrally beveled at 19, and opening through this beveled face is a port 20. This head 16 is held to the engine block in any suitable manner, as will be obvious to those skilled in the art.

Operating within the head 16 is a valve head 22 having a downwardly and centrally beveled peripheral face bearing against and rotating against the face 19. This valve head 22, as illustrated more particularly in Figure 4, is formed with a central chamber 23 communicating with an upstanding central pipe or duct 24 and exterior to the chamber 23 there is a circular concentric chamber 25 which communicates with the space 26 between the pipe 24 and the exterior pipe 27. This exterior pipe 27 has a plurality of ports 28 disposed in the same plane which communicate with an annular chamber 29, in turn in communication with the carbureter by means of the pipe 30. The central pipe 24 constitutes an exhaust passage, while the annular space 26 constitutes an inlet passage.

The inlet chamber 25 of the valve head has leading from it a plurality of radially extending intake passages 31 which open upon

the peripheral face of the valve head 22 by ports 32. The central chamber 23 or exhaust chamber has extending from it a plurality of radial ducts 33 which open upon the peripheral face of the valve head by exhaust ports 34. These ports 32 and 34 are adapted in the rotation of the valve head to register with the port 20 and to provide for the inlet of motive fluid to the several cylinders and the exhaust of the products of combustion from the several cylinders.

Assuming that there are eleven cylinders, the number of pairs of ports 32 and 34 will be equal to the number of cylinders plus one divided by two. Thus in an eleven-cylinder engine, the number of pairs of ports 32 and 34 would be six, in a five-cylinder engine it would be three, etc.

By reference to Figure 4, it will be seen that the exhaust port 34 of each pair is disposed immediately forward of the intake port 32 of the corresponding pair and that then there is a relatively long space between this inlet port and the exhaust port of the next adjacent pair. It will be seen that when the exhaust port of the valve coincides with the port 20 of a cylinder that the products of combustion will be forced out of said port by the inward movement of the piston and that then immediately the piston has reached its innermost position and is about to move outward, the inlet port 32 will move into coincidence with the port 20 and a charge will be drawn into the cylinder. The port 32 passes the port 20, the piston is then given its compression stroke and firing stroke, whereupon the next exhaust port arrives over the port 20 and the consecutive exhaust and intake strokes occur.

It will be seen by the diagram in Figure 5 that when one of the cylinders *a* is on its intake stroke and the valve corresponding thereto is fully opened, the next adjacent cylinder *b* is on its working stroke, the next adjacent cylinder *c* is beginning its intake stroke, the next cylinder *d* is on its working stroke, the cylinder *e* is three-quarters through its exhaust stroke, the cylinder *f* is compressing, the cylinder *g* is on the first half of its exhaust stroke, the cylinder *h* is compressing, cylinder *i* is at the beginning of its exhaust stroke, the cylinder *j* ending its intake stroke, and the cylinder *k* is on its working stroke. The manner in which the valve head 22 functions will be obvious from Figure 5.

It may be remarked that the speed of revolution of the valve head 22 is equal to one divided by the number of cylinders plus one, that is in an eleven-cylinder engine the speed of the valve head 22 would be equal to one-twelfth of the speed of the main or drive shaft of the engine.

Extending through the central passage 13

of the cylinder block is the main or drive shaft 35 which is mounted in suitable bearings and, as before remarked, extends through the opening 13. The cylinders 10 are concentric to this drive shaft. At its lower end the drive shaft carries an outwardly projecting arm 36 which is relatively short and this arm is connected by a ball and socket joint, bearing to a trunnion on the upper end of a shaft section 37. This shaft section carries a disk 38 and the lower end of the shaft section is connected by a universal joint 39 to a vertical post 40 extending upward from the base 41 and held from any rotation or other movement. This universal joint may be of any suitable character. The piston rods 15 of the several pistons 14 are connected equi-distantly to the margin of this disk as, for instance, by the ball and socket or universal joint connection 42. Thus it will be obvious that as the pistons move outward upon the explosion stroke they will cause an oscillatory movement of the disk 38 and the upper end of the axis of the disk will move around the shaft 35 in a circle whose radius is equal to the length of the arm 36. Thus at any position of the arm 36 the disk will be inclined to the horizontal. Those pistons which are connected to the uppermost portions of the disk will be projected into the cylinders, while those pistons which are connected to the lowermost portions of the disk will be fully retracted outward and the intermediate pistons will take, of course, an intermediate position.

As the engine functions, the disk 38 will gyrate in an obvious manner, which is permitted by the universal joint 39; and the gyration of the disk under the action of the pistons will cause the rotation of the main shaft 35. This main shaft is designed to be connected to the valve head 22 in any suitable manner so as to secure a speed for the valve head 22 of one-sixth of that of the shaft.

Any suitable gearing may be used for this purpose, but I have illustrated the main shaft 35 as carrying a gear wheel 43 of relatively small size which meshes with a gear wheel 44 three times the size of the gear wheel 43. This gear wheel 44 is mounted upon a shaft 45. This shaft carries a gear wheel 46, which in turn meshes with the gear wheel 47 carried by or operatively engaged with the rotatable valve head, this gear 47 being twice the size of the gear wheel 46. Thus the valve head will have a speed of one-sixth of the speed of rotation of the shaft 35.

The face of this valve head 22 will be formed with the oil grooves 48 whereby the valve head may be lubricated and means will, of course, be provided for securing the circulation of water through the engine block in the water spaces between the several

cylinders. The usual ignition mechanism will be used for igniting the charges within the several cylinders, the ignition being timed by means of a commutator or timer 5 operated from the main shaft in an obvious manner. I have not believed it necessary to show the ignition system, as this will be obvious to anyone skilled in the art.

Obviously the particular manner of supporting the cylinders and forming a frame for supporting the structure will be modified to suit any particular circumstances of operation and forms no part of my invention. It is to be particularly noted that 10 the beveled or conical face of the valve head 22 can be of any desired depth and inclination so as to permit relatively long valve openings to be used and, therefore, secure free passage of the gases. During 15 an explosion stroke, the pressure of the gases against the valve head is in the direction of the center of the cone so that there is comparatively slight tendency to lift the valve head and this may be readily 20 resisted by a comparatively weak spring 49 bearing down on the head and urging it to its seat. This spring will keep the valve head in air-tight contact with its seat. Furthermore, inasmuch as the valve 25 head is constantly rotating in its seat, the seating of the valve head against its seat 30 will improve with use.

It will be seen that the valve mechanism is extremely simple, that one valve head 35 may be used for any number of cylinders, that this valve is positively actuated, and provides for ample valve openings and thus ample inlet and discharge, that the shape of the valve head lends itself to lubrication 40 and cooling and that its slow rate of revolution prevents undue wear. It is also to be particularly noted as one of the advantages of this type of engine that one of the greatest causes of friction in engines is avoided, 45 that is the greatest part of the friction of the piston against the cylinder wall is eliminated. This permits a relatively long stroke of the piston without its usual drawbacks and limitations. This is due to the 50 fact that the connecting rod 15 never takes any extremely angular position with reference to the axis of the cylinder. The lower end of the piston rod takes a slightly angular relation to the axis of the cylinder, 55 but that is all. This is a very important feature of the invention and makes for economy of operation.

I do not wish to be limited to the details of construction except as defined in 60 the appended claims.

I claim:—

1. An internal combustion engine of the character described including a cylinder block formed to provide a plurality of cylinders disposed concentrically to a common

axis and parallel to each other, each cylinder having a port at one end, pistons operating within the cylinders, piston rods, a shaft with which the piston rods are operatively connected to rotate it, an annular head for the cylinder block having a centrally, downwardly and inwardly inclined seat formed with ports, one for each cylinder, and opening upon the seat, a rotatable valve head having a centrally inclined peripheral face fitting said seat and formed to provide a plurality of pairs of ports, one port of each pair constituting an exhaust port and the other an intake port, the head having a plurality of radial ducts communicating with said ports, a pair of concentric chambers into which said ducts open, axially disposed, concentric, tubular members into which said chambers open, one of said tubular members being connected to a source of fuel, and means operatively connected to the driving shaft for rotating said head. 70

2. In an internal combustion engine of the character described, a central shaft, a series of cylinders disposed concentric to the shaft, pistons operating within the cylinders and having piston rods, a support extending in axial alignment with the shaft, a wobbling shaft section having a universal joint connection to the support and flexibly connected at its opposite end to the arm on the shaft, a member carried by said shaft section to which the piston rods are flexibly connected at equi-distant points, a cylinder head common to all of the cylinders and extending over one end thereof, the cylinder head having a series of circumferential chambers registering with the several cylinders, the head having a centrally inclined inner face, there being a port opening from each cylinder to the inclined face of the head, a rotatable valve head mounted in the cylinder head and having an inclined peripheral face formed to provide a plurality of pairs of ports adapted to register with the ports in the cylinder head, the valve head being formed to provide a plurality of radial ducts extending from said ports and to provide a pair of concentric chambers into which the ports respectively open, concentric tubular members extending axially from the chambers, one of said tubular members being connected to a source of fuel, and means operatively connecting the valve head to the shaft and driving the valve head at a speed less than that of the shaft. 90

3. In an internal combustion engine of the character described, a series of cylinders disposed in parallel relation and around a central axis common to all of the cylinders, pistons operating within the cylinders and having piston rods, the upper ends of each cylinder having a downwardly and inward- 100 105 110 115 120 125

ly inclined wall, there being a port opening through said wall for each cylinder, a rotatable valve head mounted in the cylinder head and common to all of said cylinders and having an inclined peripheral face ground to fit upon the inclined faces of the upper ends of the cylinders, the valve head being formed to provide a plurality of pairs of ports adapted to register with the ports leading to the cylinders and being also formed to provide a plurality of ducts extending from said ports,

there being a pair of concentric chambers concentric to the common axis of the cylinders and into which said ports respectively 15 open, one of said chambers having means whereby it may be connected to a source of fuel and the other chamber constituting an exhaust passage, and means for operatively driving the valve head from the engine. 20

In testimony whereof I hereunto affix my signature.

CLEMENS B. NAGELMANN, M. D.
